UNITED STATES PATENT OFFICE.

EDWARD J. CURRAN, OF BATHURST, NEW SOUTH WALES, AUSTRALIA.

METHOD OF DRAFTING GARMENT-PATTERNS.

SPECIFICATION forming part of Letters Patent No. 758,826, dated May 3, 1904.

Application filed July 16, 1897. Serial No. 644,781. (No model.)

To all whom it may concern:

Be it known that I, EDWARD JAMES CURRAN, cutter, a subject of the Queen of Great Britain and Ireland, residing at Bathurst, in the Colony of New South Wales, have invented a certain new and useful Invention entitled Method of Drafting Garment-Patterns; of which the following is a specification.

This invention relates to drafting garment-patterns; and it consists in an improved method whereby the pattern for a person or figure to be fitted is obtained by accurately reproducing certain transverse contour-lines of the figure in flexible strips or mold-wires, maintaining the proper relative positions and distances of said wires, and transferring the curves or contour-lines so obtained to a pattern-sheet, which is cut on such lines to form the several templets of the entire pattern.

In carrying out the invention suitable strips or wires of lead or other flexible but inelastic material adapted to bend into and retain any desired form and hereinafter referred to as "mold-wires" are bent around the figure or person being fitted on the horizontal and certain other curves on which measurements are usually taken and are cut to proper lengths by nippers or wire-cutters. A mold or model of approximately the half-section only of the body of the person being fitted is usually taken, the mold-wires extending substantially from the middle vertical line at the back to the middle vertical line at the front; but a full-section mold of the arm is taken. The mold-wires may be held in proper relative position, and the curves or contour-lines represented thereby may be transferred to the pattern-sheet by any suitable means. As herein represented, adjacent pairs of the mold-wires in succession are arranged in marking carriers or frames which hold them at the same distance apart and in the same relative positions assumed by them when fitted around the figure. Each carrier or frame, thus having two adjacent mold-wires set therein in positions corresponding to the contour-lines which they represent, is rolled over or applied to the pattern-sheet of paper or other material or rolled over a flat surface, from which the pattern is

afterward traced, and the lines traversed by the wires held by said carrier are marked or penciled thereon in any suitable way. The paper or pattern sheet is then cut along these lines, and the several templets or transverse sections obtained are assembled in proper relation and form the whole pattern for one-half the figure. When the several transverse sections or templets of the pattern are thus assembled in proper vertical order, as shown in Figure 23, the pieces may be cut across, and the cut pieces may be secured together at their adjacent horizontal edges to form the usual vertical pattern-templets, as shown in Fig. 22.

The invention will first be described with reference to the accompanying drawings, which form a part of this specification, and will then be pointed out more particularly in the annexed claims.

In said drawings, Fig. 1 is a conventional representation of a figure or model in front view, indicating the mode of placing the mold-wires thereon. Fig. 2 is a similar side view showing the mode of setting said mold-wires. Fig. 3 represents a plan of the mold-wires or the curves obtained by the wires as molded in Figs. 1 and 2 and in their proper relative positions. Figs. 4, 5, 6, 7, and 8 are similar views, respectively, of the collar and shoulder wires, shoulder and breast wires, breast and waist wires, waist and hip wires, and wires formed to the curves of the hip and lower edge of the coat. Fig. 9 is a side view of a marking-carrier supporting the collar and shoulder wires, and Fig. 10 is a plan view thereof. Fig. 11 is a plan view of a carrier holding the breast and waist wires, and Fig. 12 is a perspective view of the same. Fig. 13 is a side view of a carrier holding the shoulder, breast, and scye wires; and Fig. 14 is a plan view thereof with the parts holding the shoulder and breast wires omitted, leaving only the attachment for the scye-wire. Fig. 15 is an enlarged side view, partly broken away and partly in section; and Fig. 16 is an enlarged fragmentary plan view illustrative of the construction of the marking-carriers. Fig. 17 is a side elevation of the vertical frame or standard with the double-jointed pointers supported thereby.

- Fig. 18 is a plan view of the standard with one of said pointers. Fig. 19 shows a carrier with mold-wires set for drafting the upper half of the sleeve, (from shoulder to elbow;) 5 and Fig. 20 shows a carrier with wires set for drafting the lower half of the sleeve. Fig. 21 illustrates a mode of applying contour-lines obtained by the mold-wires to a plane surface. Figs. 22, 23, 24, 25, and 26 represent patterns 10 or templets drafted by marking or tracing the lines traversed by the mold-wires on a plane surface or pattern-sheet. Fig. 27 is a horizontal section of the upper part of the sleeve at the scye; Fig. 28, a horizontal section 15 at the elbow; and Figs. 29 and 30 represent half-sections of the sleeve at the wrist and elbow, respectively. Figs. 31 and 32 illustrate the mode of drafting the pattern for the hip portion of a skirt.
- 20 By my improved method and apparatus it is possible to take the measurement of any kind of garment, and it will be understood that the specific habiliments illustrated herein are for explanatory purposes only and do not 25 indicate any limitation of application.
- The manner of taking measurements or applying the mold-wires to the person or figure being fitted is represented in Figs. 1 and 2. Preferably the person or figure stands with the 30 back to a vertical rod or staff C, Figs. 2 and 17, which is mounted on a fixed standard A through an arm or connecting-piece B, by means of which said rod can be adjusted both vertically and horizontally. A series of pins 35 or indicators H work in transverse holes in this rod C, and they may be secured in place by set-screws K, Fig. 18. These pins are adjusted so that their points conform to the curve of the back, as shown in Fig. 2, and 40 they indicate the relative vertical positions of points at the back on the lines or planes on or about which the mold-wire measurements are taken from the figure being fitted, the wires being molded to the figure on the horizontal 45 curves indicated by said pins or on other suitable curves not horizontal, as at the collar and shoulder. In bending or shaping the mold-wires around the body of the figure care should be taken to keep them parallel 50 and approximately horizontal to the vertical rod or staff C, and to insure this double-jointed pointers or indicators, Figs. 17 and 18, are pivotally secured to lugs D on the rod C, said pointers extending horizontally and consisting 55 each of three jointed members E, F, and G. These pointers indicate at the front of the figure places which correspond as to horizontal position with the points indicated by the pins H at the back. It is not essential that the 60 pointers should be set exactly in the same horizontal planes in which the mold-wire measurements are taken. They are intended only to act as indicators of points in horizontal planes. In Figs. 1 and 2 the mold-wires

are shown molded about the figure on suitable 65 curves at the collar and shoulder and on horizontal curves at the breast, waist, hip, and lower edge of the coat, and plans of the wires so molded are shown in Figs. 3 to 8, inclusive, which have already been explained. Any 70 suitable means, if desired, may be employed for holding the wires in proper relative positions either on or off the figure after they are molded, though this is not essential, since the wires may be molded one at a time and 75 placed aside, and afterward they may easily be arranged in exactly the same positions occupied when first molded on or around the figure by reference to the pins or indicators H and the double-jointed pointers, for it is 80 obvious that by placing the rear end of any mold-wire at the point of the proper pin or indicator H and the front end of said wire at the point of the member G of the corresponding pointer, said points having been properly set 85 before measuring the figure, the mold-wire thus arranged will represent the corresponding contour-line of the figure, and by similarly arranging an adjacent mold-wire the 90 relative positions and proper distances of the two wires may be obtained. Of course the wires may be molded on the figure without reference to the indicators and pointers described and may be arranged in proper relative positions for marking on the pattern- 95 sheet by means of other guidance or while in place on the figure, though the means described is convenient and accurate, and therefore preferred.

As before stated, in the present representation 100 of the invention adjacent pairs of the mold-wires are arranged in marking carriers or frames which hold them in their proper relative positions, said carriers having suitable devices to grip or hold the wires, which 105 devices may be adjusted to hold wires of different molds and lengths and occupying different relative positions. Each carrier, containing two adjacent mold-wires set in the same relative positions as the corresponding contour curves, is then applied to the pattern-sheet 110 in such manner as to trace the outlines of the templet or section of the figure included between said adjacent wires onto said pattern-sheet. This may be accomplished by bending 115 the pattern-sheet around the wires and marking their lines thereon or by rolling the carrier on the pattern-sheet so as to cause the adjacent wires to traverse it from end to end and marking or penciling the lines traversed. 120 The pattern-sheet is afterward cut along those lines to form the templet or pattern for that section of the garment included between the contour-lines represented by the adjacent mold-wires arranged in the carrier. Fig. 21 125 shows conventionally the mode of rolling a carrier, with its wires, over the pattern-sheet. The general construction of an efficient form

of carrier is illustrated in Figs. 11, 12, 15, and 16. This carrier, which is designed especially for holding mold-wires used for body measurements, consists of a bar or rod O, having 5 two sleeves S² adjustable or slidable thereon and secured in place by set-screws or other means and a suitable member or series of adjustable or extensible arms radiating from each sleeve and carrying at their ends spring-10 clips U or other devices adapted to grasp the mold-wires. As shown, said adjustable arms consist of tubular parts S, extending from the sleeves S², and stems T, telescopically fitted therein and provided with the spring-clips. 15 Said stems T slide in the tubular parts with a little friction, so that while they are easily adjustable yet they are sufficiently tight to hold the molded wires in proper position while the curves are being traced on the pattern-sheet. 20 The carrier here shown is formed to hold only a half-loop or semicircular mold-wire, the outermost arms thereof extending in opposite directions, it being remembered that the mold-wires are fitted to one half-section only of the 25 body of the person or figure. Figs. 11 and 12, which are plan and perspective views, respectively, show the mold-wire for the breast curve held by the upper clips and the mold-wire for the waist curve held by the lower 30 clips.

Figs. 9 and 10 illustrate in side and plan view, respectively, a carrier for the collar and shoulder mold-wires which is of somewhat different construction from that described. It 35 consists of a member D² with tubular parts F² radiating therefrom and having telescopically fitted therein stems E², provided with clips to hold the shoulder-wire, the outermost and central tubular parts F² also having at 40 their ends upright or right-angle tubular parts with stems G² adjustable therein and provided with clips to hold the collar-wire. However, the form of carrier shown in Figs. 15 and 16 could be used.

45 Fig. 13 is a side view of a carrier holding the shoulder and breast wires, together with an attachment for marking the scye or arm-hole, which is shown in plan in Fig. 14. This attachment consists of an adjustable or telescopic arm or stem V, extending from a sleeve or slider W on the bar O intermediate sliders S² and carrying a hub Y, having a universal movement, (ball, socket, and set-screw Z,) from which hub radiate a series of adjustable stems 50 or arms X, with clips to hold the scye-wire—a complete loop or circle. The clips are set so that the scye-wire will occupy its proper position relatively to the shoulder and breast wires, as in the figure being fitted. A further 55 adjustment for this same purpose is obtained by mounting arm V adjustably on a cross-arm A², extending from slider W², as shown in Fig. 14.

60 Fig. 19 shows a suitable carrier with wires

for drafting the upper half of a sleeve, the 65 same consisting of a tubular part L with stems telescopically fitted therein carrying at their ends series of radiating adjustable arms with clips for holding the mold-wires for the scye and the elbow, said series of arms radiating from balls fitted in sockets on the stem 70 for universal movement, set-screws N being provided for fixing each series of arms in position.

Fig. 20 shows a carrier with wires set for 75 drafting the lower part of the sleeve, this consisting of a bar O with sliders or sleeves P thereon having set-screws Q, said sliders having adjustable arms R radiating therefrom with clips for holding the elbow and wrist-wires. It will be observed that the arms and 80 clips of the carriers for the sleeve-patterns are adapted to hold complete loops or circles of the mold-wires, while the arms and clips of the carriers for the body-patterns are 85 adapted to hold only half loops or circles, for reasons which are now apparent.

The carrier shown in Fig. 32 for use in drafting a templet or section of the pattern for a skirt is identical in construction with the 90 carrier shown in Fig. 20.

Molds having been taken with the flexible strips or mold-wires in the manner indicated in Figs. 1 and 2, the mold-wires are then arranged in their respective marking carriers 95 or frames. First, the collar and shoulder wires are fixed in their proper carrier, which is rolled over or applied to the pattern-sheet, so as to cause the two wires to pass lengthwise or from end to end over the sheet, the 100 lines thus transversed being penciled, chalked, or otherwise marked. The marked piece or templet 1, Fig. 23, is then cut out. The ends of said templet are of course determined by the adjacent ends of the lines marked or 105 transversed by the mold-wires. Then the shoulder, breast, and scye wires are arranged in their carrier, which is rolled over the pattern-sheet in the same way, and the piece or templet 2 is thus marked off and cut out. 110 Next the breast and waist mold-wires are fixed in a carrier and the piece 3 is obtained thereby. Then the piece 4 is obtained by the waist and hip mold-wires, and so on. The several pieces so obtained are assembled in 115 proper vertical order, as shown in Fig. 23, the relative positions thereof being determined by reference to pins or indicators H. The pieces may then be cut vertically or transversely by the cutter in such lines as his experience directs and fixed in place, as shown in Fig. 22, and the adjacent vertical edges of the superposed pieces may be suitably joined, whereby the usual vertical templets conforming to the parts between vertical seam-lines of the garment are obtained. In forming a pattern for the sleeves the arms M, which 120 hold the scye-wires of the carrier shown in 125

Fig. 19, are adjusted to the angle at which the sleeve is desired to stand out from the body of the coat, and the arms for the elbow-wire are adjusted so that they radiate from the holder L at about right angles thereto. The carrier is then rolled over the pattern-sheet, as usual, and the pattern-piece for the upper part of the sleeve is thus obtained. The pattern-piece for the lower half is drafted by rolling over the pattern-sheet the carrier shown in Fig. 20 with the elbow and wrist mold-wires properly arranged. These two pieces are then placed together to form the whole sleeve-pattern, giving the length of the sleeve and widths of scye, elbow, and wrist. The seam-outlines are marked off by the cutter according to his experience.

It is practically immaterial to the operation of the main part of the invention what mechanical devices are adopted for retaining or supporting the mold-wires while the lines reproduced by them are transferred to a sheet, and I therefore do not restrict myself to the special devices herein described to be used therefor, nor is it material by what process the lines traced by the wires are reproduced on the pattern-sheet. They may be traced as described, or the wires may be inked and made to print lines, or they may be made to make impressed lines, in which last-mentioned case a glazed paper is used, the glazed surface of which will become clearly marked where it is impressed against the mold-wires. According to an alternative arrangement which I prefer to use in making patterns for ladies' habits and which may be used to obtain patterns of horizontal and other sections of a garment the wires are made to delineate the pattern while they are *in situ* on the figures. This is accomplished by using a sensitive paper for the pattern-sheet, laying it onto the figure over the mold-wires, connecting the mold-wires to one terminal of an electric battery whose other terminal is connected to a hand-plate, and moving the hand-plate over the sensitive pattern-sheet where it overlies the mold-wires, whereby the passage of the current through the sheet is facilitated and visible lines produced by the chemical change brought about by the electrolytic action. Such a sensitive sheet consists of ordinary absorbent paper kept damp and saturated with some substance whose color will change when it is electrolyzed. Such a substance might consist of a vegetable coloring-matter and common salt. When the current passes, the electrolysis of the salt produces free chlorin, which bleaches the color and leaves a white or pale line. The marked pieces so produced are manipulated in the manner already described.

Though only the drafting of a coat and skirt section has been described, it will be fully

clear that the system and apparatus may be applied to drafting patterns for trousers, 65 dresses, and other garments.

By the term "mold-wires" I refer to any suitable strips or elongated pieces of flexible or pliable material adapted to be molded readily around the curves of the figure and to 70 retain the shapes imparted thereto sufficiently for the purpose of my invention. Lead strips or wires of sufficient hardness and thickness to retain their forms are admirably adapted for this purpose. Care should be exercised 75 not to bend the mold-wires out of shape after they have been removed from the figure.

Having thus fully described my invention, what I claim as new, and desire to secure by Letters Patent of the United States, is— 80

1. Drafting garment-patterns by reproducing contour curves of the figure in mold-wires, arranging and maintaining said wires in the same relation as the contour curves which they represent, and deriving on a plane surface templets or pattern-sections from adjacent wires. 85

2. Drafting garment-patterns by reproducing contour curves of the figure in mold-wires, arranging and maintaining said wires in the same relation as the contour curves which they represent, applying them in such relation to a pattern-sheet so as to indicate thereon the outlines of the templet or garment-section included between adjacent wires, and marking said sheet on the lines indicated. 95

3. Drafting garment-patterns by fitting mold-wires or the like to the figure on certain transverse curves, arranging and maintaining pairs of adjacent wires in the same relation occupied thereby when molded on the figure, applying each pair of adjacent wires in such position to a pattern-sheet so as to trace thereon the outlines of the templet or garment-section included between said wires or the corresponding contour-lines, and assembling the several templets so obtained in proper relation. 100

4. Drafting the templet or pattern-piece of a horizontal section of a garment by molding wires on the contour curves of the upper and lower edges of the section of the figure to be fitted, mounting said wires in such manner as to preserve the same relation as said contour curves, and then applying said wires in such relation to the pattern-sheet so as to 110 trace the edges of said templet. 115

5. The improved method of drafting garment-patterns which consists in obtaining horizontal or transverse templets of the figure to be reproduced, arranging these templets in proper vertical order, and then cutting said templets along those necessary vertical lines whereby the superposed pieces when their adjacent horizontal edges are brought together will give the vertical templets of the whole 120 pattern. 125

6. Drafting the pattern of a transverse section of a garment by fitting mold-wires to the edges of said section, setting a pattern-sheet over said wires *in situ*, and electrochemically marking on said sheet the lines of contact of said wires.

5 In testimony whereof I have signed my name

to this specification in the presence of two subscribing witnesses.
